TRAVELER

Philip C. Wentworth, Providence, R. I.

Application December 10, 1942, Serial No. 468,501

2 Claims. (Cl. 57—125)

In the spinning of yarns by the ring and traveler principle, the traveler must necessarily respond to the many different strains from the bare bobbin to the full bobbin, no matter what style of building motion is used.

In recent years, many new developments have been introduced and added to the spinning frame by machinery builders. Long draft spinning has become almost universal. This new development has affected the traveler in great measure because cotton yarn especially is now being spun from a different character of roving. This roving change has been brought about by reducing processes in the card room.

The introduction of long draft spinning was accompanied by the use of larger rings and longer traverse. Larger rings and longer traverse greatly increase traveler strains and affect traveler performance materially in that in meeting these new spinning conditions, there is a greater tendency for the traveler to "ride the ring flange," due to the traveler swivelling on the ring. "Riding the ring flange" not only cuts into the traveler at a critical point, but it also gradually wears the ring flange itself and thus shortens the life of both traveler and the ring.

With these considerations in mind, I have devised my present traveler. According to it, the horns of the traveler are split and spread laterally apart a distance sufficient to stabilize the position of the traveler on the ring, without increasing frictional contact. By giving the traveler a relatively wide spread of bearing surface on the ring, the tendency of the traveler to swivel on the ring is greatly reduced. As a result, objectionable riding of the ring flange is proportionately diminished, and at the same time wear, due to frictional contact is reduced, and frictional heat is allayed.

In the accompanying drawing:

Fig. 1 is a perspective view of a traveler in accordance with my invention.

Fig. 2 is a bottom plan view thereof, and

Fig. 3 is a diagrammatic indication of a ribbon of wire traveler stock in process of being progressively developed into spread horn travelers in accordance with my invention.

In the drawing I have indicated at 10 the bow of my traveler, and at 11 the traveler horns generally.

Each horn is split centrally as indicated at 12, and spread laterally a slight distance to provide a pair of divergent balanced webs or tips 13.

Preferably each split 12 is in the form of a V, with the apices of the V splits terminating in the

related curved portions 14 of the traveler which connect the traveler horns with the bow.

The horns are spread a distance sufficient to give the traveler a wider spread of bearing surface on the ring, thereby stabilizing its position on the ring and reducing its tendency to swivel.

Actually such spread need only be relatively slight. In Fig. 2, the horns are shown as spread but slightly beyond the bow, as indicated by the dotted lines 15 in that figure.

In producing my travelers, I prefer to follow the procedure diagrammatically indicated in Fig. 3. In that figure I show a ribbon 16 of traveler stock as having been longitudinally slotted at 17 at properly spaced intervals corresponding to the location of the traveler horns when the traveler blanks B are cut from said ribbon by making severing cuts 18 centrally across the slots.

After the traveler blanks are severed from the ribbon 16, the half-slots at each traveler horn are spread laterally by any suitable tool to produce the spread horns. This is indicated by the dotted lines 19 in Fig. 3. Thereafter the blanks are bent to traveler shape over any suitable anvil (not shown) and heat-hardened and polished.

Although I have shown the horns of my traveler as square-point in design, it is obvious that their outer corners may be of rounded design if desired.

Similarly, if desired, the bow of my traveler may be slotted, perforated, or milled off at opposite edges.

These and all such other obvious modifications in structure, design, and method may obviously be resorted to within the spirit and scope of my invention as defined by the appended claims.

What I therefore claim and desire to secure by Letters Patent is:

1. A traveler to operate in substantially stabilized horizontal position on a horizontal ring without substantial tendency to swivel and ride the ring flange, said traveler comprising a bow and terminal horns, each horn being centrally split to provide a pair of balanced ring-engaging portions, and each pair of ring-engaging portions being spread apart a distance sufficient to provide a substantially wider spread of bearing surface on the ring than would be afforded by the unspread horns of a conventional traveler of comparable size and weight.

2. The traveler of claim 1, the horns being split by V-cuts and the apices of said V-cuts extending substantially to the juncture of the horns with the portions of the traveler which connect the horns to the bow.

PHILIP C. WENTWORTH.
